FLY SWATTER

Charles L. Bell, Clinton, Iowa, assignor to Lubbers & Bell Manufacturing Company, Clinton, Iowa, a corporation of Iowa

Application February 12, 1936, Serial No. 63,524

4 Claims. (Cl. 43—137)

This invention relates to improvements in fly swatters, and more particularly to the open-mesh fabric adapted for use in the blade or striking body of fly swatters.

5 The principal object of the invention is to provide as an improved article of manufacture, a novel form of woven strand material affording the most efficacious compromise between stiffness and flexibility, that is light in weight, non-scratching or marring to finished surfaces, impervious to moisture and humidity, unaffected by ordinary changes in temperature, capable of highly decorative and pleasing color effects, and that can be economically manufactured so as to be available 10 at a relatively low price.

For many years, a material has been sought combining all of the desirable qualities above enumerated.

Among the principal commercial developments 20 along this line have been the twisted paper strand fabric of the Harley Patent No. 1,727,768 and the twisted regenerated cellulose strand fabric of the Bennett Patent No. 1,913,228. Even though they generally are sold at a slightly higher cost than 25 wire screen swatters, swatters of the paper and regenerated cellulose type have enjoyed considerable popularity, due largely, perhaps, to the more pleasing decorative color effects produced, and less liability to scratch or mar polished surfaces. Still another form of commercial swatter 30 is the moulded rubber blade type. This type of swatter has demonstrated superior qualities in practically all requirements excepting those of lightness and economy, but the high cost of the 35 relatively heavy rubber blade has made it necessary to sell such swatters at considerably higher prices than woven fabric or mesh swatters,—almost prohibitive prices for such devices.

The invention may best be understood by reference to the accompanying drawing, in which

40 Fig. 1 is a perspective view of a fly swatter, the blade or striking body of which is constructed in accordance with my invention.

Fig. 2 is an enlarged fragmentary section of 45 the fabric used in the blade or striking body shown in Fig. 1.

Fig. 3 is a view similar to Fig. 2, but showing a modified form of fabric.

In the drawing, the fly swatter shown in Fig. 1 50 comprises a blade or swatter body 10 and a wire stem or support 11 having a handle 12, all of any suitable form. The blade is made of an open mesh fabric consisting of a plurality of strands 13 woven in the usual manner, having its lower 55 corners folded at 14 over the wire stem and suit-

ably secured thereon as by staples 15. The edges of the fabric are preferably secured by a suitable binding 16, sewn or otherwise secured over the ends of the strands so as to keep them from un-twisting.

5 In the form shown in Figs. 1 and 2, said fabric is woven wholly from strands, each of which consists of a thin strip of sheet "Pliofilm" twisted or rolled upon itself. This sheet "Pliofilm" material is a transparent colored or uncolored slightly extensible film, sheet or strip composed entirely or largely of rubber derivative, and is commercially available in thin transparent sheets varying approximately from .0010 to .0015 inch in thickness, at price ranges substantially less than for 10 regenerated cellulose of equal thicknesses. It is wholly moistureproof so that its resistance to moisture is not decreased by wrinkling or twisting, as is the case with regenerated cellulose which is usually given special surface treatment in 15 sheet form to improve its moistureproof qualities. Therefore, a mesh fabric made of "Pliofilm" retains uniform flexibility and rigidity within ordinary temperature and humidity ranges.

20 Due to its rubber composition, "Pliofilm" is 25 slightly extensible and considerably more pliable than paper or regenerated cellulose, so that the improved fabric of my invention provides a more elastic or resilient striking surface, less liable to mar or scratch polished furniture or the like. 30 This greater pliability also renders the fabric easier to handle in folding over and securing the fabric to the fly swatter stem or support during the manufacturing processes, particularly as compared with the more brittle regenerated cellulose 35 fabric which is difficult to crease or fold without breaking the more brittle strands. My improved material also has substantially greater tear resistance, and this, coupled with its pliability and extensibility, makes it possible for the fabric to 40 stand more abuse than the paper or regenerated cellulose strand fabrics heretofore employed in fly swatters. The improved fabric may be woven in a wide variety of colors, all having a brilliant transparent or semi-transparent appearance especially attractive to the eye. In short, the new form of material combines the ideal qualities of the high-cost moulded rubber blade with the best qualities of the lighter regenerated cellulose woven 45 fabric blade, but at a cost less than either.

50 In the form of fabric illustrated in Fig. 3, certain strands 17 are shown as made of "Pliofilm", while other strands 18 are made of twisted paper or similar material. This or similar combinations of material may be used where the greater du- 55

rability, rigidity and flexibility of the "Pliofilm" may be employed to enhance these desirable characteristics in a composite fabric of the character described.

5. Although I have illustrated and described certain embodiments of my invention, it will be understood that I do not wish to be limited to the exact construction shown and described, but that various changes and modifications may be made 10 without departing from the spirit and scope of my invention as defined in the appended claims.

I claim:

1. In a fly swatter, a blade consisting of a fabric including a plurality of strands, some of 15 which are formed of a rolled and twisted strip of thin, slightly extensible material composed entirely or largely of rubber derivative, said strands being woven together, and producing a light, pliable, resilient, scratch-proof striking body, the 20 relative rigidity and flexibility of which is substantially unaffected by moisture.

2. In a fly swatter, a blade consisting of a fabric

including a plurality of strands, some of which are formed of a thin sheet of Pliofilm composed entirely or largely of rubber derivative rolled and twisted upon itself, and producing a light, pliable, resilient, scratch-proof striking body, the 5 relative rigidity and flexibility of which is substantially unaffected by moisture.

3. In a fly swatter, a blade consisting of a fabric woven with strands, each formed of a thin sheet of transparent semi-extensible material 10 composed entirely or largely of rubber derivative rolled and twisted upon itself, and producing a light, pliable, resilient, thoroughly scratch-proof and moisture-proof striking body.

4. In a fly swatter, a blade consisting of a 15 fabric woven with strands, each formed of a rolled and twisted thin sheet of Pliofilm, composed entirely or largely of rubber derivative and producing a light, pliable, resilient, thoroughly scratch-proof and moisture-proof striking body. 20

CHARLES L. BELL.
